UNITED STATES PATENT OFFICE

WILLIAM E. WHITE, OF CHICAGO, ILLINOIS, ASSIGNOR TO KALMAN STEEL COMPANY,
OF CHICAGO, ILLINOIS, A CORPORATION OF DELAWARE

BRIDGING FOR JOISTS

Application filed December 5, 1928. Serial No. 323,898.

My invention relates to bridging for joists and beams and particularly to an improvement on the construction shown in my pending applications Ser. No. 312,324 filed October 13, 1928, Serial No. 323,897, filed December 5, 1928, and Ser. No. 328,898, filed December 28, 1928.

An object of the present construction is to provide a combined bridging unit in which a single element absorbs both tension and compression stresses. An element that will absorb the compression stresses must of necessity be rigid and not easily bent, and such an element does not, therefore, readily adapt itself to attachment to the joists. I have combined with the compression strut, an attaching clip composed of a different type of element, preferably one constructed of heavy wire having some resiliency.

The clip element is preferably arranged to be readily attached to the strut in the field, in order that the struts and clips may be packed and shipped separately.

The construction also includes numerous other features of importance which will be described in connection with the accompanying explanation.

The invention will be more readily understood by reference to the accompanying drawings, in which

Fig. 1 is a side elevation, with the beams in section, of an assembly such as contemplated by me; and

Fig. 2 is a perspective view of a unit, two of which are employed in the assembly.

In the drawings I have shown two beams or joists A—B which may be part of a series used for supporting a floor. These may consist of ordinary rolled flanged shapes or of trussed shapes.

The bridging of my invention comprises a pair of combined units arranged in diagonally disposed relation as shown in Fig. 1, one of said units being now described in detail.

The compression strut is a rigid member, preferably of channel form having a web 10 and flanges 11. At both ends the web is notched as at 12—13, the notches being shaped to permit engagement with the flanges of the

respective beams A—B. The web of the strut is provided with relatively large apertures 14—15 located on the center line at a point directly in the rear of the bottom of the notches 12—13. These struts will be constructed in the shop and the length will be exactly that required to span the diagonal space between the upper flange of one joist and the lower flange of properly spaced adjacent joists.

If the channel is of uniform section, the neutral axis or center of gravity of the section is at the center and the inner edge of the notch terminates at this point; thus the compression load is applied concentrically. Likewise, the punched holes for the reception of the hooks are located at the center and this location insures concentric application of the tension stresses.

As an attaching means, I provide clips preferably composed of heavy wire and comprising a length of material bent into U shape, the legs 16—17 being slightly flared and terminating in the hooks 18—19 adapted to engage over the flanges of the joist. To facilitate engagement, the terminal portions 20—21 of the hooks are rebent to provide an inclined surface that will engage the edge of the flange.

The clips are so constructed that they may readily be caused to engage with the apertures in the struts by a simple movement, the final position being that shown in the drawings. The clips being designed for a specific flange width, the dimensions will be such that a thoroughly firm and rigid connection will result.

The application of the bridging element is made by applying the clips in position on the strut, then engaging the clip on the lower end of the strut with the flange of the joist with the strut in the position shown in dotted lines in Fig. 1. With the parts properly designed, the connection will be fairly rigid with the parts in that position. Thereafter the operator will swing the free end of the strut laterally to avoid interference with the joist B and will then forcibly lift it to a point where the notch 12 is opposite the edge of the upper flange of the strut B. He will then swing

the free end of the strut laterally into the position shown in Fig. 1 with the wire clip swung backward in the dotted line position. The clip will then be swung up until the inclined portions 21-20 rest on the top edge of the flange and blows by a hammer will result in the engagement shown in full lines in Fig. 1. Thereafter, the operator may, by blows of a hammer, bend the portions 20-21 into the dotted line positions of Fig. 1. This will serve to tighten and lock the parts in position against removal without distortion of the clip.

The operation of oscillating the strut from the dotted line to the full line position will place the clip at the lower end under extreme tension and avoid any possible looseness. The flare of the legs of the clip provide for slight inaccuracies in dimensions; a slight initial bow in the wire of the legs 16-17 may also be utilized to compensate for such variations.

In cases where accidental spacings of the joists occur, variations are necessary only in the length of the struts and this is accomplished by providing a quantity of extra-length struts notched and apertured at one end and plain at the opposite end. A simple hand-operated tool may be used for cutting off, notching and aperturing the opposite end to the required length.

Bridging elements such as described may be very simply and economically installed. They consist of a minimum number of parts and combine the functions of a more intricate system in a simple and economical manner.

Variations in the form and arrangement of the parts may be made without departure from the spirit of my invention, and I do not wish to be limited except as indicated in the appended claims.

I claim:

1. In bridging for spaced joists, the combination of an inherently rigid strut adapted to extend between the flanges of said joists, and separate hooks attached to the ends of the strut and adapted to engage over the said flanges.

2. In bridging for beams, the combination of a rigid strut, and hooks hingedly connected to the ends of the strut.

3. In bridging for beams, the combination of a rigid strut, of angular cross section, and hooks hingedly connected to the ends of the strut.

4. In bridging for beams, the combination of a rigid strut, and wire hooks connected to the ends of the strut.

5. In bridging for beams, the combination of a rigid strut and wire members connected to the ends of the strut, and adapted to be fastened around the flanges of the beams.

6. In bridging for beams, the combination of a rigid strut having notched ends, and wires connected to the ends and adapted to

serve as means of attachment of the struts to said beams.

7. In bridging for flanged joists, the combination of a strut having notches in its ends adapted to engage flanges of said joists, and wire hooks connected to said strut and adapted to connect the strut to said joists. 70

8. In combination, a rigid strut having notches in its ends, said notches being adapted to engage the edges of the flanges of joists, and means hingedly connected to the ends of the strut adapted to engage over the joist flanges to provide a tension connection between adjacent joists. 75

9. In combination, a rigid strut having notches in its ends, said notches being adapted to engage the edges of the flanges of joists, and hooks hinged to the ends of the struts and adapted to engage over the joist flanges. 80

10. The combination with a pair of joists of a rigid strut the ends of which are in abutting engagement with the flanges of said joists to resist compression stresses, and hooks hinged to the ends of the struts and engaging over the joist flanges and adapted to receive tension stresses and transmit the same to said struts. 85

11. The combination with a pair of joists of a rigid strut, means for connecting said strut to the chord of one joist with capacity to receive and transmit compression and tension stresses, the opposite end of said strut having abutting engagement with a flange of an adjacent joist, and a wire hook pivotally mounted at said opposite end with capacity for snap-on engagement with the opposite edge of the joist flange that is engaged by the abutting end of the strut. 95

12. In combination, a rigid strut the ends of which are adapted for abutting engagement with the inside edges of the flanges of adjacent spaced joists, and wire hooks hingedly connected to the ends of said strut, said hooks being adapted for snap-on engagement with the outside edges of the said joist flanges. 100

13. In combination, a rigid strut having a flange and web, the end of the web having a notch the inner end of which terminates at substantially the neutral axis of the section of the strut, and a hook having a pivotal connection with the strut at substantially the neutral axis of the section. 115

In testimony whereof I have affixed my signature.

WILLIAM E. WHITE.
